UNITED STATES PATENT OFFICE.

NINKO SPANOVIC, OF DUQUESNE, PENNSYLVANIA.

PIPE WRENCH.

Application filed January 27, 1927. Serial No. 164,081.

My present invention relates to improvements in pipe wrenches of the class employing a movable and removable outer jaw and a stationary or fixed jaw, in combination with an oscillatable, circular head, and a non-traveling rotary nut retained in the head by the shank of the movable outer jaw. The movable jaw is adapted to be tipped on the axis of the circular head when the wrench is used, to insure an efficient grip on the pipe or other round object. A spring 5 detent is utilized in connection with the circular head for maintaining it normally in position and to permit the necessary oscillation of the head when the movable jaw is tipped.

By the utilization of the novel combinations and arrangements of parts of the device of my invention a wrench is provided 20 which is neat in appearance; properly balanced and symmetrically arranged as to the weight and location of its parts; and which is provided with a smooth exterior of proper shape to insure convenience and comfort to the user while manipulating the wrench. Due to the simplicity in construction and compact arrangement of parts the wrench may readily and with facility be 25 adjusted for use with various diameters of pipes and made to firmly grip the pipe or other round object for effective use.

The invention consists in certain novel combinations and arrangements of parts as will hereinafter be more fully set forth 30 and claimed.

In the accompanying drawings I have 35 illustrated one complete example of the physical embodiment of my invention wherein the parts are combined and arranged according to the best mode I have thus far devised for the practical application of the principles of my invention.

Figure 1 is an exterior view of a wrench embodying my invention.

Figure 2 is an edge view of the wrench as seen from the left in Figure 1.

Figure 3 is a sectional detail view, partly in elevation, showing the operating parts of the wrench.

Figure 4 is a transverse sectional view at line 4-4 of Figure 1 showing the face of the non-traveling nut.

Figure 5 is a sectional detail view at line 5-5 of Figure 1 showing the end of the 50 threaded shank in the recess of the body of the wrench.

Figure 6 is a sectional detail view of the circular head.

Figure 7 is a sectional detail view of the circular head at line 7-7 of Figure 6.

The outer movable jaw 1 is fashioned integral with a head 2, and the threaded shank 3 is adapted to be inserted in and is removable from the interior recess 4 of the hollow body 5 of the wrench. A handle 6 is extended from the hollow body and is used in manipulating the wrench, the shank 3 being adapted to move the jaw 1 with relation to its complementary fixed jaw 7. The fixed jaw 7 is preferably attached to the body of the wrench and is therefore fashioned with a tongue 8 that seats in a complementary slot 9, and the transversely extending rivet or pin 10 passing through the walls of the slot and the tongue, secures the jaw in fixed relation to the body of the wrench.

The threaded shank 3 encased within the hollow body that forms a frame, is movable to change the relation between the movable jaw and the fixed jaw, and this shank is also adapted to be tipped or oscillated to insure a firm grip of the two jaws on the object, as a pipe, when the wrench is being used.

Within the hollow body of the wrench a circular opening 11 is provided for the reception and accommodation of a circular head 12 which is adapted, within limits, to oscillate in the openings of the walls of the hollow body, which openings are filled by the head. The head retains the shank 3 and for this purpose is provided with a pair of aligned slots 13, 13 through which the shank may move freely and the head is also provided with an open, transverse slot 14 for the accommodation of a round, non-traveling nut 15, that engages the threaded shank to move the latter and adjust the movable jaw with relation to the fixed jaw. The nut is turned as usual between the thumb and first finger, and to guide the thumb and finger, and protect them, in manipulating the nut I provide concave lugs or wing portions 16 arranged in pairs at each side of the circular head. These lugs are arranged in pairs at opposite sides of the wrench body and also in pairs at opposite sides of the traveling nut, and the curvature of the lugs conforms to that of the nut. Thus the thumb and finger may be guided by the lugs to the periphery of the nut for turning the

latter, and the lugs prevent the finger or thumb from being pinched or caught by the nut while the latter is being turned. It will be apparent that the inner adjoining faces forming the opposite walls of the open slot 14 are enlarged by the use of the lugs 16 to provide increased and ample bearing surface for guiding the rotary movement of the nut 15 when the movable jaw is being adjusted. 10 Spring 19 with lug 18 in the cam socket 17 holds the movable jaw at the zero point of oscillation to either side. The first action of the spring assists in grasping the pipe by pulling the movable jaw closer to the fixed 15 jaw by the application of the wrench to the pipe. The second action of the spring, or the oscillation on the other side of the zero point helps to release the hold from the pipe by pulling the movable jaw away from the 20 fixed jaw. Both actions of the spring bring the oscillation back to the zero point because of the fact that the lug 18 is being wedged between the walls of the socket under tension of the spring.

25 By applying the wrench on a pipe, the oscillation starts at zero and goes to one extreme before the pressure is applied to the handle 6, and then when the working pressure is applied on the handle the oscillation 30 goes from one extreme across the zero point to the other extreme. When pressure is finally released from handle 6 the oscillation goes back to zero, or the normal point.

35 The oscillating head is normally held in position by means co-acting with the socket 17 in the head, which socket is provided with cam or inclined walls for guiding the detent 18 into co-action with the socket. The detent is carried at the end of a flat spring 19 40 which is secured by screw 20 within the hollow body of the wrench, and the spring exerts its tension to hold the detent in the socket and prevent oscillation of the circular head. The spring 19 through its engagement 45 by the detent 18 with the socket 17 of the circular head, provides for a double ac-

tion on the movable jaw. When not in use the spring normally tends to hold open the movable jaw, and it is adapted to disengage the movable jaw from the work after pressure has been released from the wrench jaws.

50 On the exterior of the body of the wrench I provide circular recesses 21 for the accommodation of the thumb or finger, and at the end of the handle 6 an opening or hole 22 55 is fashioned for the purpose of hanging up the wrench when not in use.

Having thus fully described my invention what I claim as new and desire to secure by Letters Patent is:—

60 1. In a wrench, the combination of a hollow body having a head and circular openings in its walls, a circular head in said openings having a transverse slot opening at one side of the head, a circular nut in the circular head, a fixed jaw on the body, a movable jaw having a shank threaded into the nut and passing through said circular head, a pair of concave lugs on the exterior of and at opposite sides of the circular head 65 for guiding the finger and thumb to the nut, said circular head having a socket, a spring in the hollow body, and a lug on said spring engaging the socket for the purpose described.

70 2. In a wrench, the combination of a hollow body having a head with openings in its walls, an oscillatable head in said openings having a transverse slot opening at one side of the head, a nut in the oscillatable head, a fixed jaw on the body, a movable jaw having a shank threaded into the nut and passing through said oscillatable head, and a spring engaging the oscillatable head to 75 normally hold it in at its center of oscillation, to apply the movable jaw to the work, and to disengage said jaw from the work when the wrench is in use.

80 In testimony whereof I have affixed my signature.

NINKO SPANOVIC.
